UNITED STATES PATENT OFFICE.

NEAL GORDON, OF VERNON, TENNESSEE.

FAN FOR CRADLES.

No. 902,071

Specification of Letters Patent.

Patented Oct. 27, 1908.

Application filed April 27, 1908. Serial No. 429,420.

To all whom it may concern:

Be it known that I, NEAL GORDON, a citizen of the United States, residing at Vernon, in the county of Hickman and State of Tennessee, have invented certain new and useful Improvements in Fans for Cradles, of which the following is a specification, reference being had to the accompanying drawings.

My invention relates to improvements in fanning devices for use over cradles, beds, dining tables and the like.

The object of the invention is to provide a device of this character which will be simple, inexpensive and practical and which may be 15 in the form of an attachment for ready application to a cradle, crib, bed, or the like.

With the above and other objects in view, the invention consists of the novel features of construction and the combination and arrangement of parts hereinafter fully described and claimed, and illustrated in the accompanying drawings, in which.

Figure 1 is a side elevation of a cradle showing the application of my invention thereto; Fig. 2 is an end view of the same; Fig. 3 is an enlarged detail view of the spring device for actuating the fan shaft; and Fig. 4 is a detail vertical section through the bearings and the arms upon the fan shaft.

30 In the drawings 1 denotes a cradle having suitably connected end members each of which is composed of two corner posts 2 united by a rocker 3 and by upper and lower horizontal bars 4, 5, the latter being united 35 by upright rods or slats 6.

My improved fanning device comprises an upright shaft 7 mounted for rotation in upper and lower bearing brackets 8, 9 secured to the bar 4 and the rocker 3. The upper 40 bearing bracket 8 has oppositely projecting end portions 10 apertured to receive fastening screws or the like 11 by means of which it is secured to the bar 4, and it has an enlarged central portion 12 formed with a vertical 45 bearing opening to receive the shaft 7 and also with an intersecting screw threaded opening to receive a set screw 13 by means of which latter the shaft may be held against rotation. The lower bracket 9 is in the 50 form of a step bearing and is composed of an enlarged central portion 14 having a socket to receive the lower end of the shaft and projecting end portions 15 apertured to receive fastening screws or the like 16 which attach 55 it to the rocker. The shaft is removably arranged in said bearings and in order to

prevent it from being casually lifted I preferably arrange upon it beneath the upper bearing 8 a slideable and removable stop collar 17 adapted to be secured by a set screw 17a. 60

The upper end of the shaft or rod 7 projects above the top of the cradle and carries a horizontal arm 18 adapted to support a suitable fan 19. Said arm 18 is vertically adjustable on the shaft by providing at its inner end a head 20 formed with a vertical opening to slidably receive the shaft and also with an intersecting threaded opening to receive a set screw 21 by means of which the arm may be held in an adjusted horizontal 70 position and at an angle with respect to the cradle. While the fan 19 may be of any form and construction I preferably make it of a body portion composed of one or more pieces of fabric or other flexible material which may 75 be suitably embroidered or ornamented and which have their upper edges united by a reinforcing strip 22. The latter is connected by fastenings 23 to a bar 24 which is suspended beneath the arm 18 in a plane preferably 80 parallel therewith by links 25. The latter have their ends bent to form eyes which are engaged with eye screws in the arm 18 and eyes upon the upper ends of the fastenings 23.

By constructing the fanning device in 85 this manner, it will be seen that when the shaft is secured against rotation by means of the set screw 13 and the cradle is rocked, the links 25 will allow the fan 19 to oscillate so that the child in the cradle will be lightly 90 fanned and flies or insects will be frightened away. It will be understood that the bar 24 is comparatively heavy so that the fan will be caused to oscillate as the cradle is rocked. The vertical adjustment of the supporting 95 arm 18 upon the shaft permits the fan to be raised or lowered as desired, and the pivotal mounting of the shaft or rod 7 permits the fan to be turned to one side out of the way when not desired. 100

In order to permit the fan to be actuated manually when the cradle is quiet I preferably provide upon the lower portion of the shaft 7 a foot piece 26 and I also provide a spring 27 for actuating the shaft in one direction. The foot piece 26 has a horizontal body portion, the outer end of which is upturned and the inner end of which is enlarged and formed with a vertical opening to slidably receive the shaft and with an intersecting threaded opening for a set screw 28 by means of which the foot piece may be se- 110

cured in an adjusted vertical position on the shaft and at any desired angle with respect to the cradle. The spring 27 is preferably in the form of a coil spring and has one of its 5 ends hooked in an eye on the outer end of an arm 29 carried by the shaft. Said arm has an enlarged inner end formed with a vertical opening to slidably receive the shaft 7 and also with a threaded intersecting opening to 10 receive a set screw 30 by means of which said arm may be adjusted vertically or longitudinally on the shaft and also angularly with respect thereto. The other end of the coil spring is engaged with the clamping screw 31 15 of a U-shaped clip 32 arranged upon the bar 5 of the cradle. It will be seen that the spring 27 will tend to swing the shaft in one direction and that the latter may be actuated in the other direction by pressing against the foot piece 26. Said foot piece may also be 20 used for operating the cradle when the set screw 13 is tightened to lock the shaft against rotation.

From the foregoing description taken in 25 connection with the accompanying drawings it is thought that the construction, operation and advantages of my invention will be readily understood without a more extended explanation.

30 While I have shown and described my invention as in the form of an attachment for ready application to a cradle, crib, bed, or the like, it will be understood that it may be otherwise used and that various changes in 35 the form, proportion and minor details of construction may be resorted to without departing from the spirit or sacrificing any of the advantages of the invention.

Having thus described my invention what 40 I claim is:

1. A device of the character described comprising a bearing, an upright shaft rotatable therein, a foot piece carried by said shaft, an arm rigidly fixed to and projecting 45 at right angles from said shaft and a fan hung from said arm.

2. A device of the character described comprising a bearing, an upright shaft normally rotatable therein, a lever secured to 50 said shaft for manually operating the same, means for holding said shaft against rotation, an arm projecting from said shaft and a fan carried by said arm.

3. A device of the character described comprising a bearing, an upright shaft rotatable therein, a spring for actuating said 55 shaft in one direction, a foot piece rigidly fixed to and projecting at right angles from said shaft for actuating the same in the other direction and a fan carried by said shaft.

4. A device of the character described comprising a bearing, an upright shaft nor-

mally rotatable therein, a spring for actuating said shaft in one direction, a foot piece fixed to and projecting at right angles from 65 said shaft for actuating the same in the other direction, means for holding said shaft against rotation, an adjustable arm upon the shaft and a fan carried by said arm.

5. A device of the character described 70 comprising bearings, an upright shaft rotatable therein, means for holding said shaft against rotation, a spring for actuating said shaft in one direction, a foot piece on the shaft for actuating it in the other direction, a 75 vertically adjustable arm upon the shaft, a weighted bar, links suspending the latter from said arm, and a fan carried by said bar.

6. In a device of the character described, the combination with an object, of bearings 80 thereon, an upright shaft rotatable in said bearings, an arm on said shaft, a coil spring fixed at one end to said object and connected at its other end to said arm, a foot piece 85 slidably and rotatably mounted upon the shaft, a set screw for adjustably securing the foot piece on said shaft, a second arm carried by the shaft and a fan suspended from the second arm.

7. In a device of the character described, 90 the combination with an object, of bearings thereon, an upright shaft rotatable in said bearings, an arm on said shaft, a coil spring fixed at one end to said object and connected at its other end to said arm, a foot piece 95 fixed to the shaft, means for holding said shaft against rotation, a second arm vertically adjustable upon the shaft, links connected to the second arm, a weighted member suspended by said links and a fan carried by 100 said weighted member.

8. In a device of the character described, the combination with an object, of an upper bearing, a lower step bearing, an upright shaft rotatable in said bearings, means for 105 retaining the shaft in said bearings, a set screw in the upper bearing for holding said shaft against rotation, an adjustable foot piece upon the shaft, an adjustable arm upon the shaft, a clip upon said object, a coil 110 spring connecting said clip and said arm, a second arm vertically adjustable upon the shaft, and a fan carried by said second arm.

9. In a device of the character described, the combination of a horizontally swinging 115 arm or member, a weighted bar, pivot links suspending the latter from said arm or member, and a fan carried by said weighted bar.

In testimony whereof I hereunto affix my signature in the presence of two witnesses. 120
